Primary Examiner — Lucy Lieberman(74) *Attorney, Agent, or Firm* — Collen IP; Donald J. Ranft(57) **CLAIM**

The ornamental design for a watch, as shown and described.

DESCRIPTION

FIG. 1 is a front perspective view of a watch showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear right perspective view thereof;

FIG. 9 is a front left perspective view of the watch shown with the back cover in an open position; and,

FIG. 10 is a rear right perspective view of the watch shown with the back cover in an open position.

The portions of the watch shown in broken lines form no part of the claimed design.
